UNITED STATES PATENT OFFICE

JAMISON R. HARRISON, OF MIDDLETON, CONNECTICUT

HIGH FREQUENCY GENERATOR CIRCUIT

Application filed July 31, 1928. Serial No. 296,584.

My invention relates to high frequency generator circuit arrangements in general and more specifically to circuit arrangements wherein high frequency signaling energy of a substantially constant frequency value is produced.

An object of my invention is to provide certain improvements in electron tube circuit arrangements for generating electrical oscillations of constant frequency.

Another object of my invention is to provide a balanced vacuum tube circuit arrangement wherein a plurality of vacuum tubes may be employed for producing high frequency oscillations of electrical energy.

Other and further objects of my invention will appear from the specification to follow and from the accompanying drawing wherein is illustrated the high frequency generator circuit arrangement of my invention.

In the accompanying drawing two electron tubes 1 and 2 are represented, each having filament electrodes 3 and 7, inner grid electrodes 4 and 8, shielding grid electrodes 6 and 10 and plate electrodes 5 and 9. Filament electrodes 3 and 7 are energized by source 17. Shielding grid electrodes 6 and 10 are supplied with a source of biasing energy from source 18 through radio frequency choke coils 11 and 12 respectively. Source of energy 19 supplies a positive potential to inner grids 4 and 8 and plate electrodes 5 and 9. Radio frequency choke coil 13 excludes radio frequency energy from source 19. Inductance

14 and capacity 15 have frequency characteristics corresponding approximately to the frequency value of the desired generated frequency. A mechanically vibratile element 16 is employed for maintaining the circuit at a constant frequency value and has frequency characteristics corresponding to the approximate frequency characteristics of the common anode or plate circuit 14, 15. Conductive

members A, B, C and D are movable and arranged adjacent to mechanically vibratile element 16. Mechanically vibratile element 16 is herein illustrated as a crystal having piezo electric properties although it is obvious that any means may be employed capable of maintaining oscillations of electrical

energy at substantially constant frequency value. An adjustment *d* provides means for laterally moving conductive members A, B with relation to C, D, and thus varying the phase relationship between the two input circuits and two output circuits.

Conductive members A, B, C and D are connected to electrodes 6, 10, 5 and 9 respectively. Means are therefore provided for varying the coupling between the input circuit 6—10 and output circuit 5—9.

Adjustable contact member 20 provides means for adjusting the relative positive potential supplied inner grid electrodes 4 and 8; this adjustment should be carefully made to secure satisfactory operation. Shielding grid 6 and anode 5 of the electron tube 1 are connected to the conductive members A and C respectively which are adjacent to the same face of the piezo electric element 16. Likewise the conductive members B and D adjacent to the opposite side of the element 16 are connected to the shielding grid 10 and anode 9 of electron tube 2. When a stress is set up in the element 16 the resulting polarization induces electrical charges of opposite sign on the metallic conductive members adjacent to the two opposite faces of the element 16. Conductive members A and C, when connected to electrodes 6 and 5, will receive charges of the same sign and likewise the conductive members B and D will have charges of like sign but which are opposite in sign to the charges on A and C. When the shielding grid 6 of vacuum tube 1 is supplied with a positive potential the shielding grid 10 of electron tube 2 is supplied with a negative potential. Because of these opposite charges, the current in the anode circuit of electron tube 1 will be increasing at the same time that the current in the anode circuit of tube 2 is diminishing.

However, anodes 5 and 9 are connected to the opposite ends of the inductance coil 14 and the direction of these currents, as illustrated by the arrows 22 in the output circuit, is such as to produce an additive effect.

Four-electrode space charge grid tubes are connected in a balanced circuit arrangement and oscillations of high frequency electrical

energy are maintained by energy feedback through the vibrating crystal element 16. Conductive members A and B are the input connections of the feedback circuit and are 5 electrically connected to shielding grid electrodes 6 and 10 of vacuum tubes 1 and 2 respectively. Shielding grid electrodes 6 and 10 are supplied with a source of potential from the biasing battery 18 through the radio 10 frequency choke coils 11 and 12. Shielding grid electrodes 6 and 10 operate as control grid electrodes and inner grid electrodes 4 and 8 operate as space charge electrodes. Accordingly the inner grid electrodes 4 and 8 are 15 supplied with a suitable positive potential from the anode supply battery 19. This neutralizes the space charge grid effect around the cathode due to electron emission.

It is obvious that many modifications of 20 the high frequency generator circuit of my invention are possible without departing from the spirit of my invention and it is to be understood that my invention is not to be limited to the foregoing specification or to 25 the accompanying drawing but only as defined in the appended claims.

What I claim as new and desire to secure by Letters Patent of the United States is as follows:

30 1. In a balanced electron tube generating system, in combination, two electron tubes each having filament, grid, shielding grid and plate electrodes, a piezo electric crystal element, two pairs of electrodes in electrical 35 relation with said piezo electric crystal element and so positioned that the electrodes constituting each pair are substantially opposite each other and embrace a portion of said piezo electric crystal, sources of filament 40 and plate potential, input and output circuits for each of said tubes, a common load comprising a tapped inductance and a condenser in parallel, a variable intermediate tap connection for said source of plate potential, said grids being connected together and to a tap on said source of plate potential, the positive terminal of said source of plate potential being connected to the tapped point of said load inductance, the terminals of said 45 50 55 60 65 70 75 80 85 90 95 100 105 110 115 120 125 130 load inductance being connected respectively to said plate electrodes, said electrodes of said piezo electric crystal element being so connected that the electrodes constituting one pair are respectively connected to said shielding grid electrodes of said tubes, and the electrodes constituting the other pair are respectively connected to said plate electrodes of said tubes.

2. In a system for producing high frequency electrical oscillations of constant frequency, in combination, two thermionic electron tubes each having filament, grid, plate and shielding grid electrodes, a load circuit connected to the respective plates of said tubes, a source of potential for supplying the

filaments of said tubes, a source of plate potential connected to said plates, a source of potential for biasing said grid electrodes positively with respect to said filament electrodes, a circuit for connecting said grid electrodes together and to said filament through said source of grid biasing potential, a source of potential for biasing said shielding grid electrodes with respect to said filament electrodes, circuits for connecting said shielding grid electrodes together and to said filament electrodes through said source of shielding grid biasing potential, a piezo electric crystal element, two pairs of electrodes for said piezo electric crystal element, said electrodes being so positioned that the electrodes constituting each pair are substantially opposite and embrace a portion of said crystal and so that said two pairs are spaced from each other, circuits connecting the electrodes of one of said pairs respectively to said shielding grid electrodes, and circuits connecting the electrodes of the other of said pairs respectively to said plate electrodes.

3. In a balanced electron tube generating system, in combination, a plurality of electron tubes symmetrically arranged in two groups, each of said tubes having filament, grid, shielding grid and plate electrodes, the corresponding electrodes of the tubes composing each of said groups being connected together, a piezo electric crystal element, two pairs of electrodes in electrical relation with said piezo electric crystal element and so positioned that the electrodes constituting each pair are substantially opposite each other and embrace a portion of said piezo electric crystal, sources of filament and plate potential, input and output circuits for each of said tubes, a common load comprising a tapped inductance and a condenser in parallel, a variable intermediate tap connection for said source of plate potential, said grids being connected together and to a tap on said source of plate potential, the positive terminal of said source of plate potential being connected to the tapped point of said load inductance, the terminals of said load inductance being connected respectively to the plate electrodes of each of said groups, said electrodes of said piezo electric crystal element being so connected that the electrodes constituting one pair are respectively connected to said groups of shielding grid electrodes of said tubes, and the electrodes constituting the other pair are respectively connected to said groups of plate electrodes of said tubes.

4. In a balanced electron tube generating system, in combination, a plurality of electron tubes symmetrically arranged in two groups, each of said tubes having filament, grid, shielding grid and plate electrodes, the corresponding electrodes of the tubes composing each of said groups being connected together, a piezo electric crystal element, two

5 pairs of electrodes in electrical relation with said piezo electric crystal element and so positioned that the electrodes constituting each pair are substantially opposite each other
 10 5 and embrace a portion of said piezo electric crystal, sources of filament and plate potential, input and output circuits for each of said tubes, a common load comprising a tapped inductance and a condenser in parallel, the positive terminal of said source of plate potential being connected to the tapped point of said load inductance, the terminals of said load inductance being connected respectively to the plate electrodes of each of said groups,
 15 15 said electrodes of said piezo electric crystal element being so connected that the electrodes constituting one pair are respectively connected to said groups of shielding grid electrodes of said tubes, and the electrodes constituting the other pair are respectively connected to said groups of plate electrodes of said tubes.

5. In a balanced electron tube generating system, in combination, a plurality of electron tubes symmetrically arranged in two groups, each of said tubes having filament, grid, shielding grid and plate electrodes, the corresponding electrodes of the tubes composing each of said groups being connected together, a piezo electric crystal element, two pairs of electrodes in electrical relation with said piezo electric crystal element and so positioned that the electrodes constituting each pair are substantially opposite each and embrace a portion of said piezo electric crystal, sources of filament and plate potential, input and output circuits for each of said tubes, a common load comprising a tapped inductance and a condenser in parallel, a variable intermediate tap connection for said source of plate potential, said grids being connected together and to a tap on said source of plate potential, the positive terminal of said source of plate potential being connected to the tapped point of said load inductance, the terminals of said load inductance being connected respectively to the plate electrodes of each of said groups, means for adjusting the relative spacing of said pairs of electrodes of said piezo electric crystal element, said electrodes of said piezo electric crystal element being so connected that the electrodes constituting one pair are respectively connected to said groups of shielding grid electrodes of said tubes, and the electrodes constituting the other pair are respectively connected to said groups of plate electrodes of said tubes.

6. In a balanced electron tube generating system, in combination, a plurality of electron tubes symmetrically arranged in two groups, each of said tubes having filament, grid, shielding grid and plate electrodes, the corresponding electrodes of the tubes composing each of said groups being connected together, a mechanically vibratile element,

two pairs of electrodes in electrical relation with said mechanically vibratile element and so positioned that the electrodes constituting each pair are substantially opposite each other and embrace a portion of said mechanically vibratile element, sources of filament and plate potential, input and output circuits for each of said tubes, a common load comprising a tapped inductance and a condenser in parallel, a variable intermediate tap connection for said source of plate potential, said grids being connected together and to a tap on said source of plate potential, the positive terminal of said source of plate potential being connected to the tapped point of said load inductance, the terminals of said load inductance being connected respectively to the plate electrodes of each of said groups, said electrodes of said mechanically vibratile element being so connected that the electrodes constituting one pair are respectively connected to said groups of shielding grid electrodes of said tubes, and the electrodes constituting the other pair are respectively connected to said groups of plate electrodes of said tubes.

In testimony whereof I affix my signature.
 JAMISON R. HARRISON.
